UNITED STATES PATENT OFFICE.

ISAAC E. PALMER, OF MIDDLETOWN, CONNECTICUT, ASSIGNOR TO THE I. E. PALMER COMPANY, OF MIDDLETOWN, CONNECTICUT, A CORPORATION OF CONNECTICUT.

COMBINED COUCH-HAMMOCK AND CANOPY.

1,183,485.

Specification of Letters Patent.

Patented May 16, 1916.

Application filed July 7, 1914. Serial No. 849,529.

To all whom it may concern:

Be it known that I, ISAAC E. PALMER, a citizen of the United States, and a resident of Middletown, in the county of Middlesex 5 and State of Connecticut, have invented an Improvement in Combined Couch-Hammocks and Canopies, of which the following description, in connection with the accompanying drawings, is a specification, 10 like characters on the drawings representing like parts.

This invention relates to combined hammocks and canopies, and particularly to couch hammocks and canopy combined 15 therewith.

In order that the principle of the invention may be readily understood, I have disclosed a single embodiment thereof in the accompanying drawings, wherein—

20 Figure 1 is a side elevation of a combined couch hammock and canopy embodying my invention; Fig. 2 is a plan view thereof; Fig. 3 is an end elevation thereof; Fig. 4 is a detail of the hammock and canopy supporting means; Fig. 5 is a detail of means for connecting the hammock sides and ends, Fig. 6 is a detail showing a modified form 25 of the invention, and Fig. 7 is a detail showing a lacing and its support.

30 An important object of my invention is to provide simple means whereby a hammock and the canopy therefor may be readily attached to the hammock support in such manner that the hammock and canopy 35 may be detached therefrom or applied thereto as a substantially unitary structure.

Referring to the accompanying drawings, wherein I have shown one embodiment of the invention, the preferred form of hammock support is represented in the several figures, wherein the ridge pole or backbone is represented at 1 and the legs at 2, 2, said legs being arranged in pairs in the general manner shown in my Patent No. 641,033, 40 so as preferably to be adjustable with respect to said backbone or ridge pole 1. The legs 2 are suitably hinged at 3 to the ridge pole, preferably as disclosed in said patent and adjacent to the apex of each pair of legs 45 50 is provided a suitable hook 4. The hammock is supported by said hooks 4 in the usual manner and may be of any suitable character.

Preferably, however, it is a couch hammock, and is here shown as consisting of suspension ends 5, 5 having clue cords 6 connected 55 to rings 7 adapted to be hung upon hooks 4. The suspension ends may form portions of a continuous hammock body extending from end to end of the hammock, as in the so-called Gloucester hammock or they may 60 be attached to the hammock frame or otherwise suitably formed. I have herein represented them as attached to the frame 8, the latter being provided with any suitable seating 9 over which, if desired, may be positioned a mattress 10. I have herein represented the hammock as having upstanding sides 11, 11, which may be of substantially the same height as suspension ends, and to 65 which they are preferably detachably connected in any suitable manner, as by means of lacing 12. I have herein represented the upper edges of the sides as having spreaders 13 provided at their ends with projecting, downwardly curved prongs 14 adapted to 70 pass through gromet eyes or suitable openings 15 in the suspension ends, and preferably in the spreaders 16 thereof. The hammock may obviously be composed of any suitable material and be of any desired 75 length and proportions. That herein shown is, however, preferably adapted for use by children as a crib.

The canopy body is represented at 17, it being preferably composed of cloth and has 80 attached thereto a series of ribs 18 radiating from a central point 19. Preferably at said point is provided suitable means for attaching the canopy to the ridge pole or backbone 1 of the hammock support. Herein for the purpose I have represented a metallic yoke 20, the upstanding members of which pass on opposite sides of the backbone 1 and at their upper ends receive a cotter pin or other device 21, whereby the 85 yoke is detachably secured to the backbone or ridge pole. Obviously the said backbone or ridge pole may be of any suitable shape and material. Herein I have represented it as metallic and tubular, so that 90 the yoke 20 may rock or tilt thereon in the swinging motion of the hammock. Adjacent its ends and at substantially mid-distance between its sides the canopy is pro- 95 100

vided with two openings 22 preferably provided with gromets and the supporting hooks 4 are passed through said openings, as shown most clearly in Fig. 4. Preferably the hooks 4 are shaped substantially as shown in said figure, so that the gromets of the openings rest upon the curved portions of the hooks and the canopy body is at least partially supported thereby at its 10 end portions so as to be substantially level. Preferably the canopy is provided with depending portions 22' extending to a point below the upper edges of the suspension ends and upstanding sides, and preferably I provide means for detachably engaging said depending portions of the canopy and said suspension ends and upstanding sides. Said depending portions of the canopy may be formed of any suitable material. Herein I 15 have represented them as composed of mosquito netting or like foraminous material. In order detachably to connect the hammock and the depending portions of the canopy, I have in Figs. 1 and 3 represented at each 20 corner gathering cords 23, which are secured to the depending portions of the canopy by guiding strips 24 and which when tightened cause the depending portions of the canopy tightly to engage the suspension ends and 25 upstanding sides. If desired, and as indicated in Fig. 6, I may provide the depending portions of the canopy with spreaders or strips 25 extending transversely and longitudinally of the hammock and substantially 30 meeting at the corners thereof. In connection with said strips or spreaders, I may and preferably do employ gathering cords, such as indicated at 23.

The construction of canopy may be widely 40 varied within the scope of my invention. For example, instead of providing the same with a series of radiating ribs 18, I may provide a transverse central rib or slat extending from side to side of the canopy and two 45 end ribs or slats parallel thereto, which latter may be provided with perforations for the passage of the hooks 4. In such case, said end ribs or slats may rest upon and be supported by said hooks. Furthermore, if 50 the hammock be suspended in some manner not providing a backbone or ridge pole 1, as, for example, from two spaced objects, a cord or like connection may be connected with the suspension chains or ropes and which may 55 be positioned so that the canopy may be secured thereto by a central yoke 20 and end hooks substantially as herein shown. In such case, such cord or other connection would take the place of the rigid backbone 60 or ridge pole 1.

Having thus described one illustrative embodiment of my invention, I desire it to be understood that although specific terms are employed in the foregoing description, they 65 are used in a generic and descriptive sense

and not for purposes of limitation, the scope of the invention being set forth in the following claims.

Claims:

1. A combined hammock and canopy comprising in combination a hammock having end suspension devices, and a substantially horizontally positioned plane surfaced canopy having supporting means between its ends and provided with end openings, said 70 canopy being supported at its horizontal end portions by engagement of said openings with said end suspension devices.

2. A combined hammock and canopy comprising in combination, a hammock having end suspension means, a hammock support which said suspension means are adapted to engage and a canopy having openings at its ends for the passage of said suspension means, and pivotal, mid-length connection 80 to the hammock support.

3. A combined hammock and canopy comprising in combination, a hammock having end suspension hooks, a hammock support to receive said hooks and a canopy having 90 at its ends openings for the passage of said hooks, and a yoke adapted for pivotal connection to the hammock support.

4. A combined hammock and canopy and support therefor comprising in combination, a hammock support, a hammock having end suspension means adapted to engage said support, and a canopy having supporting means between its end portions, adapted to engage said hammock support, said hammock end suspension means passing through 100 openings in the end portions of the canopy and engaging said support.

5. A combined hammock and canopy and support therefor comprising in combination, 105 a hammock support having a ridge pole or backbone, three supporting members depending from said ridge pole and substantially in a vertical plane passing therethrough, a hammock having suspension connections to the two endmost of said supporting members, and a canopy having a supporting connection to said intermediate supporting member, and also having an operative connection with said endmost supporting members.

6. A combined hammock and canopy and support therefor comprising in combination, 110 a hammock support having a ridge pole or backbone, three supporting members depending from said ridge pole and substantially in a vertical plane passing therethrough, a hammock having suspension connections to the two endmost of said supporting members, and a substantially horizontally positioned, plane surfaced canopy having a supporting connection to said intermediate supporting member and also having end openings in its horizontally positioned ends, through which said endmost 115

supporting members pass, said canopy having its horizontally positioned ends supported by said endmost supporting members.

- 5 7. A combined hammock and canopy comprising in combination a hammock having end suspension hooks, and a substantially horizontally positioned, plane surfaced canopy having supporting means between its
10 ends and having gromets in its horizontally positioned end portions for the passage of

and adapted to be engaged by said hooks, whereby the said horizontally positioned end portions of the canopy are supported by engagement with said suspension hooks. 15

In testimony whereof, I have signed my name to this specification, in the presence of two subscribing witnesses.

ISAAC E. PALMER.
